UNITED STATES PATENT OFFICE.

CHARLES BILLY, OF PARIS, FRANCE.

DESIGN FOR A CARRIAGE-LAMP.

SPECIFICATION forming part of Design No. 34,803, dated July 16, 1901.

Application filed April 15, 1901. Serial No. 56,025. Term of patent 7 years.

To all whom it may concern:

Be it known that I, CHARLES BILLY, a citizen of the Republic of France, residing at Paris, France, have invented and produced a new, useful, and original Design for Carriage-Lamps, of which the following is a specification, reference being had to the accompanying drawing, forming a part thereof.

The drawing is a perspective view of a lamp embodying my design.

a is the rectangular base of the lamp, and *b* the horizontal cylindrical body thereof surmounting the base *a*. On the main portion of the body is supported a casing *c*, with an arched top and rounded ends which project laterally beyond the cylindrical body, and on the front end of the body is supported a smaller casing *d* of substantially the same exterior contour as the casing *c*. Extending over the casing *c* and having an arched form

is a handle *e*, the ends of which extend down to the body *b* at the sides. On the front end of the larger casing *c* is a hood *f*, of convex contour, and on the front end of the base *a* is a casing *g*, of elliptical contour.

The leading feature of my design is the base *a*, of rectangular contour, surmounted by the body *b*, of cylindrical contour, and the casings *c* and *d*, of the contour shown, surmounting the said body.

I claim—

The design for a carriage-lamp herein shown and described.

In witness whereof I have hereunto signed my name, this 12th day of March, 1901, in the presence of two subscribing witnesses.

CHARLES BILLY.
